(No Model.)

J. E. McCREARY.
STEAM BOILER AND FURNACE.

No. 451,504.

Patented May 5, 1891.

UNITED STATES PATENT OFFICE.

JONAS E. MCCREARY, OF CHICAGO, ILLINOIS.

STEAM-BOILER AND FURNACE.

SPECIFICATION forming part of Letters Patent No. 451,504, dated May 5, 1891.

Application filed December 20, 1890. Serial No. 375,380. (No model.)

To all whom it may concern:

Be it known that I, JONAS E. MCCREARY, residing at Chicago, in the county of Cook and State of Illinois, and a citizen of the United States, have invented certain new and useful Improvements in Steam-Boilers and Furnaces, of which the following is a specification, reference being had to the accompanying drawings, in which—

- 10 Figure 1 is a front elevation, a portion of the front of the boiler being broken away. Fig. 2 is a longitudinal vertical section of the forward part of my improved boiler and furnace. Fig. 3 is a detail, being a longitudinal vertical section of the smoke-conduit and a portion of the steam-inlet pipe; and Fig. 4 is a detail, being a horizontal section of a modification of the lower section of the smoke-conduit.
- 15 Only such parts of a boiler and furnace are shown as are necessary to the illustration of my invention.

The common forms of smoke-preventing steam-boilers and furnaces make use of steam conducted from the boiler to cause a current of air to flow into the furnace in order to secure a more perfect combustion by the consumption of mixed air and steam, and thus prevent the original formation of smoke. To successfully operate smoke-preventers made on this plan it has been found necessary to heat the air thus introduced into the furnace to a high temperature, both to secure more perfect mixture of the air and steam and to prevent condensation of the steam, and consequent corrosion of the boiler and loss of heat. The heating of the air and its intermixiture with the steam have been found to be great obstacles to the successful operation of such devices and add greatly to their expense.

The objects of my invention are to avoid the above objections and to provide a smoke-preventing attachment for steam-boilers and furnaces which will not require the introduction of fresh air into the combustion-chamber of the furnace except as it enters through the usual draft, but which will effectually purify the smoke before it leaves the boiler and furnace, and which will not interfere with the draft.

A further object of my invention is to pro-

vide a smoke-purifying attachment for steam-boilers and furnaces which will be inexpensive and which may be readily placed in position. I accomplish these objects as illustrated in the drawings and as hereinafter described. That which I regard as new will be pointed out in the claims.

In the drawings, A indicates an ordinary boiler, having the usual forward compartment or smoke-chamber *a*, through which the smoke passes on its way to the smoke-stack B.

C indicates a steam-pipe leading from the steam-dome to and extending across the front of the boiler, as best shown by the dotted lines in Fig. 1, which pipe C is secured to the front of the boiler and furnace in any suitable manner. The pipe C is provided at some convenient intermediate point with an ordinary stop-valve D, by which the supply of steam may be easily regulated.

Extending up a short distance into the smoke-chamber *a* of the boiler, and leading from it to the combustion-chamber E of the furnace, are one or more smoke-conduits composed of sections F F', which are preferably united at right angles, as shown in Fig. 3, and pass downward and backward through the supporting wall or inclosure of the boiler and open into the combustion-chamber E. The section F' is preferably made to end flush with the inner face of the wall of the combustion-chamber E, but may extend a short distance into said chamber if a stronger draft is desired.

The section F is preferably made square at the top and has pivoted to it near one of its upper edges a drop or butterfly valve J, which opens downward by slight pressure and is normally held in a closed position by the weight of a projecting arm or lever *j*.

Extending into the section F' of each conduit and terminating slightly beyond the lower end of the section F, as best shown in Fig. 3, is a smaller steam-pipe c, leading from the steam-pipe C. The pipe c is made smaller than the section F', so that a draft down the section F may be created by the action of the steam in passing through said pipe c, and also to permit of the passage of the smoke downward from section F through section F' into the combustion-chamber E.

In the ordinary form of boiler having the

smoke-stack in the forward end the smoke passes through the smoke-chamber *a*, and thence upward into the smoke-stack. By the use of my improved boiler and furnace when 5 the valve *D* is opened steam is admitted through pipes *C* and *c* into section *F'* of the conduit, whence, the valve *J* being normally closed, the steam escapes into the combustion-chamber *E*, causing a draft downward through 10 sections *F F'* into the combustion-chamber, which draft opens the valve *J*, and it is held open by the downward pressure created by the draft. By this means the unconsumed carbon and heavier gases are drawn by suction 15 through the conduit *F F'*, as indicated by the arrow, and into the combustion-chamber *E* of the furnace, where they are again subjected to an intense heat and produce a more nearly perfect combustion. They then 20 pass through the tubes of the boiler again and out at the smoke-stack, being heated to a higher temperature and greatly purified. With a properly-regulated steam-pressure in the pipes *C* and *c* the draft down the conduit 25 *F F'* will not draw the lighter gases into the furnace again, as such gases will be in the upper part of the smoke-chamber *a*, and will not come so readily within the influence of the draft, as the section *F* extends only a 30 short distance into the compartment or smoke-chamber *a*.

It will be noted that when the smoke first comes from the furnace it is already at a high temperature, and therefore will not materially 35 condense the steam, which also passes into the furnace. The tendency to corrode the boiler, which is common to most smoke-consuming boilers and furnaces using steam, is by this means avoided.

40 In order to better expose the unconsumed carbon and other impurities to the heat of the furnace, I preferably horizontally flatten the mouth of section *F'* of the conduit, which causes a more general distribution of the impurities throughout the furnace. The mouth 45 of section *F'* may be rounded or bell-shaped.

The inner end of the section *F'* is subjected

to intense heat, and therefore I provide this section with a detachable nozzle *f'*, which is flattened horizontally and expands toward its 50 delivery-mouth, as in Fig. 4, for the purpose of spreading and distributing the unconsumed products of combustion over the fire in the fire-box. The inner end of the nozzle *f'* is adapted to encircle the end of section *F'*, 55 as shown at *f''* in Fig. 4, and is interiorly flanged in order to make a more perfect connection. When it is desired to remove the nozzle *f'*, a portion of the brick-work of the wall which incloses the section *F'* is removed, 60 when the nozzle may be changed and the brick-work built up again.

I do not regard the use of steam as essential to the operation of my device, as any other blast may be used to create a downward 65 draft through the conduit *F F'*. The use of steam is preferable, however, owing to its convenience and to the fact that as it is already at a high temperature it will not reduce the temperature of the furnace appreciably. 70

What I claim as new, and desire to secure by Letters Patent, is—

1. In a boiler and furnace, the combination, with a smoke-conduit composed of sections *F F'*, connecting the front of the boiler with the 75 combustion-chamber of the furnace, and a downwardly-opening overbalanced valve pivoted in the upper section thereof, of a steam-pipe adapted to conduct steam from said boiler into the section *F'* of the smoke-conduit and terminating slightly forward of the section *F* of the smoke-conduit, substantially as and for the purpose specified. 80

2. The combination of the boiler *A*, smoke-chamber *a*, valve-capped tubes *F*, and horizontal tubes *F'* with the steam-tube *C*, extending down and across in front, having branch pipes *c* extending into the tubes *F'*, and the furnace-chamber *E*, substantially as and for the purpose specified. 85

JONAS E. McCREARY.
